[57] CLAIM

The ornamental design for a deck of fortune telling cards, as shown and described.

DESCRIPTION

FIG. 1 is a plan view of the faces of the spade suit of a deck of playing cards showing our new design;

FIG. 2 is a plan view of the faces of the heart suit;

FIG. 3 is a plan view of the faces of the diamond suit; and

FIG. 4 is a plan view of the faces of the club suit.

The backs of the cards are conventional.

FIG. 4
